UNITED STATES PATENT OFFICE

2,457,133

FRAGMENTARY CHARACTER PRINTER

Edmond M. Deloraine, New York, N. Y., assignor to International Standard Electric Corporation, New York, N. Y., a corporation of Delaware

Original application October 18, 1941, Serial No. 415,554, now Patent No. 2,365,458, dated December 19, 1944. Divided and this application September 6, 1944, Serial No. 552,887. In Canada June 24, 1943

1 Claim. (CL 178—30)

1

This invention relates to printing telegraph systems and more particularly to a printing telegraph for radio use. This application is a division of my copending application Ser. No. 415,554, filed October 18, 1941, now Patent No. 2,365,458, dated December 19, 1944, and is directed to the facsimile printer which may be used with the system disclosed in the said copending application.

An object of the invention is to provide a facsimile printer of rugged construction, light in weight, and adapted for portable use, especially for communication with airplanes.

Another object of the invention is to provide a facsimile printer in which the number of mechanical movements of the apparatus is limited to a very few, these being of such a nature as to render the amount of mechanical maintenance on the equipment almost negligible.

A further object of the invention is to provide a facsimile telegraph printer which will avoid the vertical displacement of the letters on the tape when there is an appreciable difference in speed between the transmitter and the receiver, such speed difference in the present invention resulting only in the slanting slightly forward or backward of the characters, the direction and degree of slant serving as a guide to indicate the direction and extent of adjustment required by the printer motor governor.

One embodiment of the invention is disclosed in the accompanying drawings in which:

Figure 1 is a schematic representation of the printer mechanism and associated circuits;

Figure 2 is a plan view of the printer chariot shown in Figure 1;

Figure 3 is a chart indicating the manner in which received impulses are formed into built up characters.

In my copending application referred to above a preferred embodiment of a transmitter is disclosed having a smooth, quiet, cam-operated mechanism of the "sewing machine" type. A drum, perforated about its circumference in a series of rows is driven uninterruptedly at a uniform rate by a motor. A key operated shutter is provided for each row of perforations, the perforations of each row being arranged according to the elements forming a character in a code. A photo electric cell is positioned within the drum

and the light from an external source is permitted to pass through the perforations of the drum to be received by the photo electric cell only when the shutters are moved to uncover the perforations. The shutters are selectively withdrawn by the manually operated keys.

The photo electric cell is connected to an amplifier, the output of which feeds a radio transmitter so that when the keys are operated a series of coded impulses are transmitted. The perforations are preferably arranged in the drum so as to modulate the light beam to produce a start impulse and a plurality of character impulses.

In a preferred form of the invention the start impulses are at a different frequency than the signal impulses so as to be able to separate them at the receiver. To do this the drum is perforated with as many rings or circumferential rows of holes as there are characters to be transmitted. The number and grouping of the perforations of any one ring is such that the beam of light directed through them from the outside of the drum to the photo electric cell inside would be modulated at approximately 540 cycles for a short interval, say 30 milliseconds for a start signal, and thereafter in a series of impulses of about 800 cycles to represent the characters.

In the preferred embodiment of the transmitter the perforations are grouped to transmit facsimiles of the characters selected. In order to do this the perforations in the drum are arranged to transmit each letter or character in seven horizontal lines, this number being selected to give a fair degree of detail when the character is recorded. With a line signal of this kind, the number of signals for each letter is consequently much higher than in the Morse or five unit code.

Figure 3 shows diagrammatically the impulse groupings for the characters "E," "2," and "N" in an arrangement where each character is divided into seven horizontal bands, impulses of the required length being transmitted in proper relative position for each band and the bands transmitted in succession for the purpose of operating the printer which has means for recording the impulses successively to form a built up character, as will be hereinafter described.

The printer as shown in Fig. 1 comprises a

motor 220 provided with known means, not shown, for maintaining a constant rate of speed sufficiently close to that of the transmitter to permit start-stop operation. In the present arrangement about to be described, speed variation within reasonable limits does not cause the printing of a wrong letter but the letters are printed slanting in one direction or the other, the direction of the slant indicating whether the speed is high or low, and the degree of slant, the speed difference. Consequently, speed adjustments are easily maintained.

Motor shaft 221 is connected to a second shaft 222 by clutch 223 consisting of a pawl 224 and ratchet 225, fixed respectively on shafts 222 and 221. Pawl arm 226 cooperates with armature 227 of start magnet 228, one terminal of which is connected to ground and the other to the front contact 229 of relay 230 which has an armature 231 connected to a grounded source of potential.

A cam 232 on shaft 222 engages a roller 233 at the end of arm 234 pivoted at 235. A link 236 connects arm 234 with chariot 237, which reciprocates horizontally in suitable guideways (not shown) under the influence of cam 232 and spring 238 connected to arm 234. In the present embodiment the chariot supports seven styli 240 which are vertically movable in apertures in the chariot against the tension of individual springs, not shown. A top view of the chariot is shown in Fig. 2.

A print hammer 241 is disposed above the chariot and a platen 242 over which passes an inked ribbon 243 and a paper tape 244. The print hammer is mounted on an arm 245 pivoted at 246 and held normally against stop 247 by spring 248. The print hammer is oscillated by magnets 250 and 251 secured between the pole-pieces 252 of a permanent magnet, the armature 253 thereof being connected to the printhead. The magnet and armature arrangement is similar to that of a balanced armature loud-speaker unit.

One terminal of magnets 250-251 is connected to the amplifier 211 by circuit 255. The other is connected to contact 257, the tongue 258 therefor being connected via circuit 256 to the amplifier. Relay 230 has one terminal connected to the amplifier via circuit 255 and the other by contact 259, tongue 258 and circuit 256, only when the cam is in stop position, tongue 258 being moved away from contact 257 and into engagement with contact 259 by an insulating pin 260 carried by cam 232 which engages the tongue just as the cam reaches stop position, as shown in the drawing.

The printer operates as follows. Assuming the printer and transmitter motors are running at the proper relative speeds and that the transmitter key has been depressed for the letter "E" sending out a series of spaced impulses commencing with the cycle start signal, as shown in Figure 3.

On receipt of the start signal which enters the receiver 210 and passes through the filter and amplifier 211, indicated by the block diagram of Fig. 1, relay 230 is momentarily energized and operates start magnet 228 by a circuit from its tongue through front contact 229 and the windings of the start magnet to ground. The operation of the start magnet withdraws its armature 227 out of the path of the arm 226 of pawl 224, and the pawl in response to pressure from a spring, not shown, engages the teeth of ratchet 225 causing shaft 222 and cam 232 to rotate.

The rotation of the cam carries arm 234 and

chariot 237 toward the right of the drawing, the cam being so synchronized with the transmitter drum that each stylus 240 operated for the first band traverses a distance over the platen 5 while under the printhead equal to the width of a letter while the first band is being transmitted, and then passes beyond the printhead. The first band is followed by the second band. During reception of the second band each stylus 10 operated moves under the hammer so that on operation thereof the stylus contacts the paper tape making a mark in said second band, and so on, for the remainder of the bands.

As the printing of a letter progresses, cam 232 15 moves arm 234 further to the right until the seventh and last stylus has completed its travel under the printhead. Shortly thereafter the high part of the cam passes from under roller 233 and the arm is snapped back to the left by spring 238.

A pawl 265 connected to arms 234 and 268 by 20 pivots 266 and 267 respectively, arm 268 being supported on a pivot 269, is used to operate a tape feed mechanism. During the movement of arm 234 to the right, the pawl drops behind a tooth in a ratchet wheel 270 provided with a detent, not shown, secured to a roller which cooperates with a pressure roller 271 between which rollers paper tape 244 passes. The reverse movement of arm 234 to the left causes the pawl 30 to turn the ratchet and advance the tape a distance of one letter space. Suitable means, not shown, are used for feeding the ribbon.

On the completion of the reception of a letter, cam 232 carries insulating pin 260 into engagement with contact tongue 258, breaking the circuit to magnets 250 and 254 and connecting the amplifier via contact 259 again to start relay 230 to await reception of the next start impulse.

40 Pawl arm 226 of the clutch strikes armature 227 disconnecting the pawl from the ratchet 225 and stops rotation of the cam until reception of the next start pulse.

The movement of the styli is very sensitive and 45 the printhead follows the signalling currents accurately, the characters being printed to conform to the perforations in the transmitter drum. In a printer of the kind described, the only non-printing function required is the word space and 50 the space bar of the transmitter when operated merely causes the transmission of a start signal causing the receiver to start and stop in the manner above described, and since no impulses are transmitted to actuate the printhead the 55 unmarked tape is advanced the distance of a word space.

While the present invention has been disclosed with reference to specific embodiments thereof, it will be understood that these embodiments are 60 merely presented by way of example and that many modifications of the invention will be suggested thereby to those skilled in the art without departing from the spirit or scope of the invention.

What is claimed is:

In a facsimile printer a record surface comprising a paper tape, a stationary platen therefore, an inked ribbon disposed over said tape, a printhead disposed over said platen means 70 for moving said printhead in response to signal impulses, a chariot, a guideway in which said chariot may move between said printhead and inked ribbon, a plurality of diagonally disposed styli movably supported in said chariot and arranged when struck by said printhead to

cause said ribbon to mark the paper tape, a pivoted arm arranged to be oscillated, a link connecting said arm to said chariot whereby the chariot is moved in said guideway corresponding to the movement of said arm, a single-cycle rotary cam swinging said arm uniformly in one direction for printing and releasing it for rapid return, and means operated by said arm in its return movement to feed the paper tape.
